DOOR FOR TRAP NESTS

Lawrence E. Vaa, Poulsbo, Wash.

Application November 22, 1933, Serial No. 699,236

2 Claims. (Cl. 119—49)

This invention relates broadly to trap nests and more particularly to an improved door therefor.

An object of the present invention is to provide a door for nests of the character above mentioned which may be readily used either as a "lock out" door or as a "trap" door; and also a door of this character which may be mounted for use in conjunction with nests now installed requiring little or no alterations to the old nest; 10 and further a door which will be tripped by the hen entering the nest so as to automatically close behind the hen.

The invention together with its objects and advantages will be best understood from a study 15 of the following description taken in connection with the accompanying drawings wherein:

Figure 1 is an elevational view viewing the door from the outside of the nest, and showing the door in closed condition.

20 Figure 2 is a sectional view taken substantially on the line 2—2 of Figure 1 and with the door in closed condition.

Figure 3 is a detail sectional view taken substantially on the line 3—3 of Figure 1.

25 Figure 4 is an enlarged sectional view taken substantially on the line 4—4 of Figure 1 but with the door in open position.

Figure 5 is a view similar to Figure 1 but viewing the door, in closed condition from the inner 30 side of the door and

Figure 6 is a fragmentary detail sectional view taken substantially on the line 6—6 of Figure 5.

Referring to the drawings by reference numerals it will be seen that 10 indicates generally 35 the trap nest. The entrance and exit opening for the nest 10 is indicated by the reference numeral 11.

As previously set out the present invention is concerned especially with an improved door for 40 closing the opening 11 and the door is indicated generally by the reference numeral 12.

For mounting the door 12 there are provided two substantially U-shaped hinge-clips 13, 14 adapted to straddle the wall 10a of the nest at 45 the lower edge of the opening 11, and these clips 13, 14 are formed from a single length of wire a portion 15 of which connects the inside legs of the clips as suggested in Figures 4 and 5.

Cooperable with the clips 13, 14 are substantially triangular shaped brackets 16, 17 which are, at one side thereof, secured to the top side of the door 12 by U-shaped or other suitable type of fasteners 18. The brackets 16 and 17 at their enlarged ends are adapted to engage the outside 50 of the wall 10a in a manner suggested in Figure 4

for limiting swinging movement of the doors 12 downwardly and to an open position. These brackets 16, 17 are also formed from a single length of wire the ends 19, 20 of which are bent inwardly towards one another and are journalled in curved portions 21 provided in the clips 13, 14, as shown in Figure 4. With the ends 19, 20 thus journalled in the parts 21 of the clip an efficient hinge is provided for the door 12.

For normally urging the door 12 to swing upwardly to a closed position there is provided a spring 22 disposed about one of the ends 19 and having one end bearing against the underside of the door 12 as at 23, and a second end 24 bearing against the outside surface of the wall 15 10a in a manner suggested in Figure 1.

For releasably retaining the door in the open position, or the position shown in Figure 4, one of the clips, in the present instance the clip 14, has the outer leg thereof extended downwardly beyond the fasteners 25 and bent upwardly as at 26 to provide what may be termed a keeper for co-operation with the latch 27 on one of the brackets, in the present instance bracket 16, which at the junction of the vertical and inclined portion 25 thereof is bent laterally outwardly as at 27 to engage under the keeper 26 as suggested in Figure 4 in a somewhat automatic manner, upon swinging movement of the door 12 to the open position or position shown in Figure 4 for releasably retaining the door 12 in said open position.

The wire from which the brackets 16, 17 are formed is so twisted or shaped as to connect the said brackets by a cross bar 28 that normally extends above the door 12 as shown in Figure 4 35 so as to move downwardly under the weight of a hen entering the nest in a manner to move the latch 27 out of engagement with the keeper 26 whereby the door under action of spring 22 will automatically swing upwardly to a closed position 40 relative to the opening 11 behind the hen.

In order to insure the utilization of the weight of the hen for effecting this automatic release of the door there is provided a treadle plate 29 which is shaped or stepped as shown in Figure 4 45 to provide a vertical part merging into an attaching flange 29a that is loosely secured to the top of the door 12 at the hinge end thereof by staples 29c, and a treadle flange or part 29b that overlies and normally rests on the bar 28 as shown in Figure 4. Obviously with the door in the open position shown in Figure 4 the hen upon entering the nest will step upon the part 29b of the treadle plate and the weight of the hen will cause the bar 28 to move downwardly for releas-

ing the latch 27 permitting the door to swing to the closed position as above stated.

To secure the door in closed position from the outside of the nest there is provided a suitable closure means which in the present instance consists of a keeper pin 30 that projects from one edge of the door and with which is engageable the hook shaped end of a suitable latch member 31 rockably mounted on the wall of the nest 10 10 adjacent the opening 11 as at 32.

The door 12 at the free edge thereof is provided with a notch 33 which will accommodate the head and neck of the hen in a manner to permit the hen to open the door when leaving the nest. In this connection it will be apparent that with the door closed and the hen is desirous of passing from the nest the hen may pass its head and neck through the notch 33 in a manner to push the door downwardly and outwardly to an open position. As the door thus swings to an open position the hen is free to pass outwardly through the opening 11 and upon swinging of the door 12 to a fully open position the latch 27 will automatically engage with the keeper 26 in a manner to retain the door in open position until the door is closed either manually or by the re-entrance of the hen in a manner above suggested.

When it is desired to use the door as a "trap" door so as to retain the hen within the nest a cover plate 34 may be brought into use for closing the notch 33. The cover plate 34 is made of metal or other suitable material and is provided at its upper edge with a channel 35 that engages the edge of the door 12 at the open end of the notch 33 in a manner to substantially close the notch. (See Figure 2.)

Having thus described my invention, what I claim as new is:

1. A nest of the character described having in combination a wall provided with an opening, U-shaped clips straddling the wall at the lower edge of the opening, a door for closing said opening, resilient bracket members for the door secured

thereto, and provided with pintles journaled in said clips for hingedly mounting the door on said wall, interengaging means on one of said clips and on one of said brackets for releasably retaining the door in an open position, and a treadle member mounted on the door and engageable with said latter bracket in a manner to release said inter-engaging means automatically by a hen entering the nest, whereby the door is released to swing to a closed position behind the hen. 10

2. A nest of the class described having a front wall provided with an opening, a door for said opening, an integral clip structure including a pair of spaced substantially U-shaped hinge clips 15 straddling said wall at the lower edge of the opening, an integral bracket structure for the door comprising a pair of spaced parallel substantially triangular brackets secured to the door and a U-shaped connecting part adapted to extend vertically and in adjacent parallelism with the wall when the door is in open position, and with the closed end of the U projected upwardly from the plane of the door, said bracket at the end thereof connected by said U-shaped part being 20 provided with inwardly extending pintles journaled in said clips for hingedly supporting the door from the wall at the lower edge of said opening, and a treadle member mounted on the door and having a part arranged to engage said 25 U-shaped connecting part of the bracket structure when the door is in open position, and inter-engaging latch means on one of said clips and at the junction of one of the brackets and the U-shaped connecting part of the bracket structure for releasably retaining the door in open position, said inter-engaging means being disengagable by the weight of the hen on the treadle to release the door, and spring means engaged with the door to swing the same to a closed position upon release of said inter-engaging means. 30
